UNITED STATES PATENT OFFICE.

WILLIAM E. PRICE, OF WHITE PLAINS, NEW YORK, ASSIGNOR TO AURORA BEACON CORPORATION, OF NEW YORK, N. Y., A CORPORATION OF NEW YORK.

SIGN.

Continuation of application Serial No. 60,159, filed October 3, 1925. This application filed October 3, 1925.
Serial No. 60,160.

This invention relates to signs. More particularly the invention is directed to a sign of improved construction adapted for use in advertising, show room display, as indicators, 5 markers, and for other like purposes.

One object of the invention is to provide a sign of the character described of improved construction as to enable same to be suspended and used as a hanging sign or reversed and 10 rested on a support, and having legend plates which may be interchanged, reversed, or replaced.

Another object of the invention is to provide an improved sign of the character described comprising few and simple parts, which shall be neat, attractive, and artistic in appearance, inexpensive to manufacture, and practical and efficient to a high degree.

Other objects of this invention will in part 20 be obvious and in part hereinafter pointed out.

Certain features herein shown and described are shown, described and claimed in my co-pending application Serial No. 60,159 25 filed on the 3rd day of October, 1925, the present application being a continuation of said co-pending application.

With the above exception, the invention accordingly consists in the features of construction, combinations of elements and arrangement of parts which will be exemplified in the construction hereinafter described, and of which the scope of application will be indicated in the following claims.

35 In the accompanying drawing, in which is shown one of the various possible illustrative embodiments of this invention,

Fig. 1 is a front elevational view of a sign embodying the invention in suspended position;

Fig. 2 is a cross-sectional view taken on line 2—2 in Fig. 1;

Fig. 3 is a cross-sectional view showing an enlarged detail view taken on line 3—3 in 45 Fig. 1;

Fig. 4 is a cross-sectional view of the sign shown resting on a support; and

Fig. 5 is a cross-sectional view taken on line 5—5 in Fig. 1.

50 Referring in detail to the drawing, 10 denotes an electrically illuminated sign embodying the invention, and which is seen to comprise a casing 11 having legend plates 12 which form the closures for the front and

rear sides thereof. The ends of the casing 55 are provided by parallel triangularly shaped members 11^a, connected together at their apex portions 11^b by a cross bar 11^c, the base portions thereof being connected by a removable cover 11^d which forms a closure for the 60 side of the casing opposite said bar 11^c as shown in Figs. 1 and 2. The end members 11^a, bar 11^c, and cover 11^d are joined together to form a rigid structure in any well known manner, as by means of lug and screws 13. 65

For removably retaining the legend plates 12 in place, each end member 11^a is provided with an inturned flange 11^e and the edge portions thereof and the adjoining edge portions of the bar 11^c and cover 11^d are each provided with rim grooves 14 for slidably receiving said plates. Thus the legend plates form enclosing sides for the casing and may be dismounted by simply removing the cover 11^d for interchanging said plates and for reversing them when the sign is reversed from the suspended position shown in Figs. 1 and 2 to a standing position shown in Fig. 4. Spaced legs 19 projecting outwardly from each of the end members 11^a provide convenient means for supporting the sign 10 in either position, said legs serving as ear members for a chain 19^a or as a base for the sign as will be readily understood.

For lighting the interior of the sign, an 85 electric lighting fitting 15 having lamps 16 housed within the casing and mounted on the cover 11^d is provided and connects with a suitable power source (not shown) through conductor wires 16.

90 Each legend plate may be made in any well known manner to have the legend formed with opaque lettering with a translucent background or with translucent lettering with an opaque back-ground. In the form here shown and more fully described in my aforementioned application, said plate 12 comprises a sheet of metal, fibre, composition or other suitable material preferably forming a relatively stiff backing.

95 A desired legend 20, or a display device in the form of letters, symbols, or ornamentation is outlined or stencilled on said sheet and said legend cut out in any well known manner. A strip 17 of flexible fabric such as 100 textile fabric, paper, or other like material which is translucent or may be made so, is applied to the rear side 12^a of the sheet 12,

and portions 17^a of said strip are drawn through the cut out portions of the backing member 12 so as to project beyond the front side thereof. The legend or device is thus given the effect of being raised or embossed. For artistic effect, the projecting or intaglio surfaces 17^a of said projecting portions are preferably left uneven and irregular to simulate rough cut stone. To secure the strip 17 and intaglio surface 17^a in a fixed position, a suitable adhesive such as sodium silicate, shellac, varnish, lacquer, or other like substance is employed and preferably is applied to both sides of the strip. Thus the strip 17 may be china silk and coated with sodium silicate. The latter then also serves as a fire resistant. Shellac, varnish, or lacquer is preferably used in place of the sodium silicate as an adhesive and coating where the sign is exposed to moisture. To waterproof a sodium silicate-coated strip, a surface coating of shellac, varnish, or lacquer may be provided.

Any of the aforementioned substances when applied to the strip and dried is effective to stiffen the intaglio portions 17^a for retaining them in their proper shape, said portions then forming what is commonly termed an "unbreakable" structure which is highly efficient as a light diffusing medium, being relatively thin and translucent because of its texture.

For holding the unattached portion 12^b of the backing sheet 12, incorporated in the legend, against accidental displacement, bowed bridging arms 18 are provided for anchoring said portion 12^b to the rear side of said sheet, said arms being made of transparent material or of relatively thin wires which can cast only imperceptible shadows across the translucent legend.

On the interior side of the backing sheet 11^a, the uncut out portion thereof may be provided with a suitable light reflecting surface, as for example white paint or metallic foil, to increase the interior illumination of the sign. To produce various lighting effects such as color effects and the like, the lamps 16 may be colored and may be provided with automatic circuit making and breaking means in the well understood manner, or slide holding means 21 may be provided on the rear side of the plate 12^a for removably holding a color slide 22 over the cut-out portions of the backing member 12. The outer background surface of the plate 12 may be given any desired finish by painting, polishing, plating, engraving, covering with a textile fabric, or hammering to form a pebbled surface.

It is apparent that the sign 10 constructed as above described is very practical since it can be easily, simply and inexpensively fitted with legend plates having styles of lettering to suit any individualistic taste and is adapt-

ed to be selectively suspended or reversed and supported from below.

It should be noted that by reason of its substantially triangular cross-section, the sign when suspended above the level of the observer's eye normally holds the legend plate closer to a plane perpendicular to the line of vision than it would if the plates were in a vertical plane, and similarly when the sign is reversed and rests on a support below the level of the observer's eyes, the legend plate is also positioned closer to a plane perpendicular to the line of vision. The legend, such as elaborate lettering, symbols, and ornamentation is thus clearer and more legible and the sign more effective. Also it has been found that signs with convergently disposed legend plates lighted from the interior as shown and described have greater illuminating efficiency than similar signs with parallelly extending legend plates.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:—

1. A sign of the character described comprising a casing having end members and cross members rigidly connecting said end members, one of said cross members being substantially wider than the other and adapted to support means for illuminating the interior of the casing, a legend plate removably secured to form a side closure for said casing, and projections at the longitudinal edges of the wider cross member having provision for mounting the sign in a depending position, said projections serving as a broad base to rest the sign on a support when turned upside down.

2. A sign of the character described, a casing having triangularly shaped end members, a cross-bar connecting the apexes of said members, a cover member extending between the sides of said members opposite the apexes, lighting means mounted on said member for illuminating the interior of the casing, and a plate having translucent portions forming a legend removably supported to form a side closure for said casing.

3. A sign of the character described comprising a casing having end members and cross members connecting said ends, one of said cross members being substantially wider

than the other and adapted to support means for illuminating the interior of the casing, and a legend plate removably secured to form a side closure for said casing, and projecting means formed integral with the casing for selectively mounting the casing to permit sloping the plate downwardly or upwardly away from an observer as and for the purpose described and specified.

10 4. A sign of the character described, a casing having triangularly shaped end members, a cross-bar connecting the apexes of said members, a cover member extending between the sides of said members opposite the apexes, lighting means mounted on said cover member for illuminating the interior of the casing, and a plate having translucent portions forming a legend removably sup-

ported to form a side closure for said casing, and projections adjacent the cover member 20 for mounting the casing in a depending position, said projections serving as legs to rest the sign on a support when said sign is turned upside down.

5. A sign of the character described comprising a casing having substantially triangular end members, a wide cross-member connecting the base sides of the end members, a narrow cross-member connecting the apex portions of the end members, projections 25 integral with the wide cross-member for resting said sign on a support, said projections having provision for suspending the sign.

In testimony whereof I affix my signature.

WILLIAM E. PRICE.
